UNITED STATES PATENT OFFICE.

THOMAS C. ANDERSON, OF MOSCOW, NEW YORK.

RAILWAY-TIE.

SPECIFICATION forming part of Letters Patent No. 470,094, dated March 1, 1892.

Application filed April 24, 1891. Serial No. 390,255. (No model.)

To all whom it may concern:

Be it known that I, THOMAS C. ANDERSON, of Moscow, in the county of Livingston and State of New York, have invented a new and 5 Improved Railway-Tie, of which the following is a full, clear, and exact description.

My invention relates to improvements in railway-ties; and the object of my invention is to produce a cheap and durable metal tie 10 which is constructed in such a manner that it may be easily laid, that it will hold the rails securely in place, that it may be easily adjusted in any kind of weather so as to bring a rail into a desired position as regards height, 15 and which has all the elastic qualities of wood.

To this end my invention consists in a railway-tie constructed substantially as herein-after described and claimed.

Reference is to be had to the accompanying 20 drawings, forming a part of this specification, in which similar figures of reference indicate corresponding parts in all the views.

Figure 1 is a broken sectional plan of a railway-tie embodying my invention with rails 25 secured thereon. Fig. 2 is a broken vertical longitudinal section through the tie and rails. Fig. 3 is a cross-section on the line 3-3 in Fig. 2. Fig. 4 is a broken side elevation showing 30 a device for securing the ends of the rails and preventing them from separating; and Fig. 5 is an end view of the same, showing the rail in section.

The tie 10 is composed of two separable parts 11 and 12, each of which is substantially 35 rectangular in shape, and each of which is hollow and open on one side, the lower part 11 being open at the top and the upper part 12 at the bottom. The parts are constructed so that the upper portion 12 will fit closely 40 within the lower portion 11, and to prevent the upper part from sliding it is preferably made somewhat shorter than the lower part, and the part 11 is provided near the ends with lugs 13, which are secured to its inner walls 45 and overlap the walls of the upper part 12. The upper part 12 of the tie is provided near opposite ends with clips 14, which are preferably struck up from the metal forming the tie, and these clips are adapted to fit over the 50 flanges of the rails 15 and have their ends

strike against the webs of the rails. In connection with these clips other clips 16 are used, which are arranged on the outside and inside of the rails, the outside clips serving as an additional guard on curves, so that if 55 the clips 14 should break the rails would still be held. The clips 16 are pivoted, as shown at 17, to the tie, and they are adjusted so that when swung against the rail their ends will abut with the web thereof, and the clips are 60 held in place by bolts 18, which extend downward through the clips and through the upper portion of the tie.

Near each end of the upper portion 12 of the tie are inclined bridges 19, which have 65 their ends 20 bent at an angle and firmly bolted to the side walls of the part 12. Beneath these bridges 19 are wedges 21, the bevel of which corresponds with the inclination of the bridge 19, and to prevent the withdrawal 70 of the wedges small lugs 22 are formed on or secured to the upper side of the tie-bottom. It will thus be seen that when the rails are in place upon the upper portion of the sleeper the wedges may be driven inward and the 75 part 12 of the tie will rest upon the wedges, thus giving to the tie the same elasticity that a wooden sleeper has, as the wedges are preferably made of wood. The wedges also afford means for adjusting the tie vertically. The 80 rails are secured in place upon the tie by sliding them sidewise under the fixed clips 14 and then securing the clips 16 in the manner already described.

In Figs. 4 and 5 I have shown a device in 85 which the ends of the rails may be secured, and which prevents the rails from spreading. It comprises a rectangular hollow sleeper 23, which is open at the bottom, and which has at the top a plate 24 with inclined lugs 25 on 90 opposite sides thereof, and the lugs are shaped to fit the flange of a rail and rest against the web, as best shown in Fig. 5. The sides of the sleeper are long enough to extend between two ties, and the top plate 24 projects from 95 the ends and is adapted to rest upon the tops of the ties. The sleeper is secured to the ties. The ends of the rails are held between the lugs 25, and are thereby prevented from separating.

Having thus described my invention, I claim as new and desire to secure by Letters Patent—

1. A railway-tie consisting of two vertically-separable parts and wedges for separating the parts, substantially as described.
2. A railway-tie comprising two vertically-separable parts, the upper of which has inclined bridges near the ends, and wedges adapted to fit between the bridges and the bottom portion of the tie, substantially as described.
3. The combination of the two parts 11 and 12, the part 11 having lugs on the bottom and

the part 12 having inclined bridges near its ends, and wedges adapted to fit between the bridges and the tie-bottom, substantially as described.

4. A railway-tie comprising two vertically-separable parts adapted to close one within the other and means for adjusting the parts in relation to each other, substantially as described.

THOMAS C. ANDERSON.
